MATERIAL STRAIGHTENING APPARATUS

Aeneas J. N. Duclos, South Orange, N. J., assignor
to Western Electric Company, Incorporated,
New York, N. Y., a corporation of New York

Application April 29, 1942, Serial No. 441,039

6 Claims. (Cl. 153—54)

This invention relates to material straightening apparatus, and more particularly to apparatus for measuring lead covered cable and straightening the cable so that the measurement thereof may be accurate.

The lack of rigidity in lead covered cable and other like materials as well as the weight thereof, renders such structures difficult to measure accurately due to their natural tendency to bend while being advanced or to retain a portion of the curved contour when being withdrawn from a supply reel.

An object of the invention is to provide an apparatus which is simple in structure and highly efficient in straightening material.

With this and other objects in view, the invention comprises a guide for an advancing material and sets of straightening rolls mounted for variation in relative positions for receiving materials of different sizes to straighten the materials during advancement thereof.

Other objects and advantages will be apparent from the following detailed description when considered in conjunction with the accompanying drawing, wherein

Fig. 1 is a top plan view of the apparatus;

Fig. 2 is a side elevational view of the apparatus;

Fig. 3 is a fragmentary sectional view taken along the line 3—3 of Fig. 1, and

Fig. 4 is a vertical sectional view taken along the line 4—4 of Fig. 2.

Attention is now directed to the drawing, wherein reference numeral 10 designates in general the frame of the structure, shown having a table portion 11 formed of suitable material such as metal angles. Legs 12 supporting the table portion may also be formed of angle members and secured to the table portion 11 with suitable reinforcing members. A bracket 14 of a suitable structure is mounted at one end of the table, to support a guide 15 for material to be straightened and measured, such as a lead covered cable 16. In the present embodiment the material or cable is advanced from a supply reel and by suitable means (not shown) through an aperture 17 in the guide 15, the aperture being flared outwardly toward the entrance end thereof to readily receive the cable from different relatively angular directions and allow free movement of the cable therethrough. After leaving the guide 15 the cable passes between a pair of grooved rolls 18, these rolls being mounted on suitable shafts 19 supported by a transverse member 20 mounted upon the table

portion 11. The grooves, indicated at 21, in the rolls 18 are of sufficient cross-sectional dimensions to receive the largest cable (as shown) and will efficiently guide this as well as smaller cables during their advancement.

After the cable leaves the rolls 18 it passes between a set of straightening rolls 23, these rolls having V-shaped grooves 24 in their peripheries, as illustrated in Fig. 2, to receive cables of various sizes, that is, of various cross-sectional dimensions. The rolls 23 are rotatably mounted on shafts 25, the latter being disposed adjacent the ends of a supporting element 26 of the contour illustrated in Figs. 1 and 3.

15 At the center of the supporting element 26 a pivot 28 is provided therefor, the pivot being in the form of a stub shaft mounted in a cross member 29, the latter being mounted upon the table portion 11. A spring 30, having one end 20 fixed to the supporting element 26 adjacent one of the shafts 25 and the other end fixed to the member 29, normally urges the supporting element with the rolls counterclockwise, to normally urge the adjacent end of the element in engagement with an adjustable locating screw 31. The screw 31 is threadedly disposed in an internally threaded bracket 32 mounted upon the table portion 11. A handle or hand wheel 33 is mounted upon the outer end of the screw 31, to assist 25 in the adjustment of the screw for variations in the positions of the rolls 23, relative to the path of advancement of the material.

Another set of rolls 35, identical in structure with the set of rolls 23, with V-shaped grooves 36 in the peripheries thereof is mounted upon shafts 37. The shafts 37 are mounted in the ends of a supporting element 38 which is identical in contour to the element 26, the element 38 being mounted at its center upon a pivot 39, 40 the latter being supported by a bracket 40. The bracket 40 is of the contour illustrated in Figs. 1 and 2 and is mounted on the end of the frame 10 to position the rolls 35 to receive the cable during its advancement, these rolls, however, 45 being disposed in a plane at right angles to the rolls 23. In other words, the axes of the rolls 35 lie in a plane at right angles to the axes of the rolls 23. The supporting element 38 is also provided with a spring 41, to normally urge one 50 end of the element in engagement with an adjustable locating screw 42, one end of the spring being fixed to the element, the other end fixed to the bracket 40. The screw 42 is disposed in an internally threaded portion 43 of the bracket 40, a handle or hand wheel 44 being mounted

upon the outer end of the screw 42 to assist in the rotation thereof.

Interposed between the sets of rolls 23 and 35 is a counter mechanism, indicated generally at 46, and including a counter unit 47 of the conventional type actuatable by a counter wheel 48, the latter being rotatably supported for engagement with the portion of the cable between the sets of straightening rolls. The counter unit and the counter wheel are supported by a bracket 49, the latter being mounted on a cross member 50 for lateral adjustment by any suitable means (not shown) through the assistance of screws or bolts receivable in elongate aperture 51 of the cross member to locate the counter wheel 48 in proper engagement with the surface of the cable during its advancement from one set of rolls to the other. A yoke 52, to assure positioning of the cable in engagement with the wheel 48, is grooved for the cable and has a dovetail or other connection 53 with the bracket 49 where it is mounted for vertical adjustment by an adjusting screw 54.

In preparing the apparatus for operation the size of the cable to be measured and straightened is first determined, after which the sets of straightening rolls are adjusted and, if necessary, adjustments made in the counter mechanism. The grooves 21 in the rolls 18 as well as in the aperture 17 in the guide 15 are of sufficient size to receive cables of various sizes to be straightened. It is important that the relative positions of the rolls in each set of straightening rolls 23 and 35 be varied depending upon the size of the cable, so that they may effectively straighten the cable for its advancement relative to the counter mechanism. With the straightening rolls in the position shown, they are located for the largest cable to cause bending of the cable in right angular planes to effect straightening of the cable. A large cable, in passing between the straightening rolls, will travel farther away from the shafts or axes of the rolls than will a smaller cable travel, and for this reason it is necessary that the elements 26 and 38 supporting the rolls 22-23 and 35-35 respectively be moved a greater distance counterclockwise to create a sufficient bending action for the straightening operation. If, however, a smaller cable is to be measured and straightened, the locating screws 31 and 42 are turned sufficient and like distances to vary the location of the supporting elements and thus vary the positions of the straightening rolls relative to the path of advancement of the material or cable. The springs 30 and 41 function to maintain the elements 26 and 38 respectively in engagement with their respective locating screws.

In straightening lead covered cable it is not necessary to give as severe a reverse bend to cable as it passes between the sets of straightening rolls as would be necessary for more resilient materials such as steel wire. The cable passing through the apparatus appears to be straight at all portions but it should be borne in mind that a cable withdrawn from a supply reel and entering the guide 15 at varying angles with respect to the center line of the guide, will not be straight. It is through the functioning of the sets of straightening rolls that the bends are taken out of the cable and the cable is made straight. It, therefore, should be understood that although the cable in advance of the first set of straightening rolls appears straight in the drawing, it is not truly straight, and to il-

lustrate such in the drawing so that it would be readily noticeable would require exaggeration of the contour of the cable. It is believed apparent that with this apparatus materials of various sizes may be straightened during advancement to make possible the accurate measurement of the material.

Although specific improvements of the invention have been shown and described it will be understood that they are but illustrative and that various modifications may be made therein without departing from the scope and spirit of this invention as defined by the appended claims.

What is claimed is:

15. A material straightening apparatus comprising supporting elements formed to receive pivots for their support, separate pivots received by the elements to support their elements in different planes angularly disposed relative to each other, pairs of rolls for the elements, and separate means carried by the elements to rotatably support the rolls of each pair equal distances from their pivots to cause their rolls to engage different sides of material advancing longitudinally between the pairs of rolls.
20. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, and means to move the elements about their pivots to simultaneously vary the positions of the rolls of each pair relative to the said path.
25. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, and means to move the elements about their pivots to simultaneously vary the positions of the rolls of each pair relative to the said path.
30. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, and a locating member for each element adapted to locate its respective element and rolls in variable positions relative to the path of the material.
35. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
40. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
45. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
50. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
55. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
60. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
65. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
70. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.
75. A material straightening apparatus comprising supporting elements formed to receive pivots for their support, separate pivots received by the elements to support their elements in different planes angularly disposed relative to each other, pairs of rolls for the elements, separate means carried by the elements to rotatably support the rolls of each pair equal distances from their pivots to cause their rolls to engage different sides of material advancing longitudinally between the pairs of rolls, a locating member for each element adapted to locate its respective element and rolls in variable positions relative to the path of the material, and resilient means to hold each element in engagement with its locating member.

rate means carried by the elements to rotatably support the rolls of each pair equal distances from their pivots to cause their rolls to engage different sides of material advancing longitudinally between the pairs of rolls, and threaded members mounted for engagement with their respective elements to adjust the elements about their pivots to simultaneously vary the positions of the rolls of each pair relative to the said path.

6. A material straightening apparatus comprising supporting elements formed to receive pivots for their support, separate pivots received by the elements to support their elements in different planes angularly disposed relative to each

other, pairs of rolls for the elements, separate means carried by the elements to rotatably support the rolls of each pair equal distances from their pivots to cause their rolls to engage different sides of material advancing longitudinally between the pairs of rolls, threaded members mounted for engagement with their respective elements to adjust the elements about their pivots to simultaneously vary the positions of the rolls of each pair relative to the said path, and resilient means to hold each element in engagement with its threaded member.

AENEAS J. N. DUCLOS.
